JAMES C. RHODES, OF STILLWATER, MINNESOTA

Letters Patent No. 73,386, dated January 14, 1868.

IMPROVEMENT IN CRUTCHES.

The Schedule referred to in these Letters Patent and making part of the same.

TO ALL WHOM IT MAY CONCERN:

Be it known that I, JAMES C. RHODES, of Stillwater, in the county of Washington, and State of Minnesota, have invented a new and useful Improvement in Crutches; and I do hereby declare that the following is a full, clear, and exact description thereof, which will enable those skilled in the art to make and use the same, reference being had to the accompanying drawings, forming part of this specification.

This invention relates to a new and improved device for preventing the end of a crutch from slipping on ice or other slippery places; and it consists in arranging an adjustable spur or point in the end of the crutch, as will be hereinafter described.

Figure 1 represents a longitudinal central section of a crutch, constructed according to my invention.

Figure 2 is a cross-section, through the line *z z* of fig. 1.

Similar letters of reference indicate corresponding parts.

The main feature of my improvement is securing a rod in the crutch, the lower end of which shall have a point or spur attached, while the upper end shall be within reach of the hand, and so arranged that it may be made to protrude beyond the lower end of the crutch, or be drawn up above it, with an arrangement whereby it may be fastened in either position.

A represents the rod; B is the point or spur, which is larger in diameter than the rod. In the lower portion of the crutch there is a tube or recess, *a*, and in this recess there is a spiral spring, *c*, which bears against the upper end of the recess, and against the spur or point, which forms a shoulder on the rod, as seen in the drawing. In this position the tendency of the spring is to force the spur and rod down, as it bears on the shoulder with a constant pressure. To prevent the spur from being forced too far out, and to provide means for holding it up in the recess *a*, above the end of the crutch, I attach plates *C*, *D*, and *E*, to the crutch, between the branches, as seen in the drawing. These plates are secured together by screws *e e*.

On the top or upper end of the rod *A* there is a sleeve, *d*, into which the rod is screwed or fastened, and through the sleeve *d* there is a pin, *f*, which projects, as seen. The middle plate *D* is slotted, so as to allow this projecting pin to pass through it when the pin is turned in the right position. In the plates *C* and *E*, which are placed above and below the plate *D*, there are circular recesses, as seen in fig. 2, so that when the rod is raised to the upper recess, the spur *B* will be withdrawn from the end of the crutch, when, by giving the rod a partial turn, by the handle *G*, the pin will be turned from the slot in the plate *D*, and rest upon its upper side, thus holding the rod in that position, or with the spur withdrawn.

When it is desired to use the spur, it is only necessary to turn the rod, so that the pin will enter the slot in *D*, when the spring will force it down till it strikes the lower plate *E*, and a partial turn of the rod fastens it in that position. The rod *A* may be raised and lowered by a screw-thread cut on it, engaging with a nut in the place of the plates, or with a nut in some other position. I do not therefore confine myself to the particular arrangement shown.

The handle *G* forms a permanent rest for the hand of the person using the crutch, so that he can instantaneously project or retract the spur without changing the grasp of his hand. The spur in crutches is much more important to the person using than appears to people who have no need of crutches. It should always be kept sharp as possible, so as to penetrate ice or slippery timber easily when wanted. To do this it must be withdrawn while walking on stone sidewalks, or the point will be ground off, so as to be useless, in a very short time.

But having thus described my invention, what I claim as new, and desire to secure by Letters Patent, is—

The handle *G*, in combination with the rod *A*, spur *B*, and the devices for projecting and retracting said spur, substantially as set forth.

JAMES C. RHODES.
